UNITED STATES PATENT OFFICE.

JOHN THORNBER, OF BRADFORD, ENGLAND, ASSIGNOR TO BRADFORD DYERS' ASSOCIATION LIMITED, OF BRADFORD, ENGLAND.

FABRIC-GUIDING DEVICE.

1,282,985.

Specification of Letters Patent. Patented Oct. 29, 1918.

Application filed August 9, 1916. Serial No. 113,939.

To all whom it may concern:

Be it known that I, JOHN THORNBER, a subject of the King of Great Britain, and resident of Bradford, in the county of York, 5 England, have invented a certain new and useful Improvement in Fabric-Guiding Devices, of which the following description, having reference to the accompanying sheets of drawings, is a specification.

10 My invention relates to devices or mechanism whereby the guiding or feeding of fabrics to stentering or like machines may be carried out in such a manner as to keep same straight and even as is well known, 15 and the object of my present invention is the production of these devices or mechanism of such a character as to enable them to act efficiently with little inconvenience to the user, while their cost of production as 20 compared with devices as heretofore employed, is comparatively little.

My said invention consists in the employment of a disk at one or both edge or edges of the fabric, each of such disks being freely 25 mounted on an axis that occupies a position approximately at right angles to the plane in which the fabric travels while it is so placed that the fabric which it has to guide will travel over half or nearly half of the 30 flat surface of said disk thus causing same to rotate and to effect a lateral pull upon the fabric.

35 Preferably I employ in conjunction with said disks, runners or bowls which rest thereon and which by lever devices are controlled in their actions according to the position of the fabric being guided.

In order that my said invention may be 40 readily understood, I have hereunto appended sheets of drawings, illustrative thereof wherein:

Figure 1 is a sectional end elevation of my improved parts showing same mounted upon brackets extending from the certain movable 45 parts of the machine to which said devices are applied.

Fig. 2 is an elevation of parts shown by Fig. 1 as seen in the direction indicated by the arrow α .

50 Fig. 3 is an end elevation illustrating the form of bracket I secure to the fixed frame-

work of the machine for supporting the cross bars shown by Figs. 1 and 2.

Fig. 4 is a plan of the parts illustrated by Fig. 2.

55 Fig. 5 is a plan drawn to a reduced scale showing my apparatus mounted in position as upon the two sides of a machine so that the fabric being fed thereto will have both of its edges guided by same.

60 B indicates the brackets extending from the movable parts of the machine to support my improved devices as hereinafter explained, and C indicates the brackets secured to the fixed framework of the same machine.

65 In carrying my invention into effect I make use of a pair of disks 2, 2^a, one disk being mounted on one side of the machine while the other disk is mounted on the opposite side of the machine. These disks 2, 2^a 70 are arranged to revolve freely in bearings 3 with their upper surfaces somewhat in the horizontal plane or in that plane in which the fabric b they have to guide, travels. The bearings 3, upon which the disks 2, 2^a are 75 mounted, are made so that they may be regulated to adjust said disk at any desired angle to the horizontal plane, as the extent to which it may be necessary for them to pull upon the fabric they are to guide may determine. The axial shafts 2^b of the disks 2, 2^a are arranged to revolve as stated in the 80 bearings 3 while they extend above the upper surfaces of said disks 2 in order to have mounted upon them bearings 4, 4^b which by 85 the axial pins 4^a mounted upon said bearings 4, 4^b support a series of runners 5, 5^a. The bearings 4, 4^b are mounted to slide loosely upon the axial shafts 2^b in order that the runners 5 may rest upon the upper 90 surface of the disks 2, 2^a, thus enabling the fabric b passing between said runners 5 and the disks 2, 2^a to transmit motion to said disks 2, 2^a and runners 5, 5^a as will be understood.

95 Connected to the bearings 4, 4^b are arms 6, 6^a which by having beveled quadrant teeth 7, 7^a are connected to corresponding quadrants 8, 8^a pivoted at 8^b upon bearings 9, 9^a secured to the bearings 3 upon which the 100 disks 2, 2^a are mounted. As the fabric b is being fed in the direction opposite to that

indicated by the arrow *a* (Fig. 1) it passes firstly beneath the roller 10, over the roller 11 and under the roller 12 in order to rest upon the upper surface of the disks 2, 2^a at 5 each side of the machine. The rollers 10, 11 and 12 are mounted upon the brackets 13 and 13^a secured to the fixed framework of the machine to which my improved devices are applied.

- 10 The bearings 3 are arranged to be carried by the brackets B fixed upon the bearings upon which are mounted the sprocket wheels which operate the stentering chains—so that when said chains are adjusted for narrower 15 or broader fabrics so also will my guiding devices be adjusted.

The actions of the several parts are as follows:—After the attendant has passed the fabric over the two disks and beneath 20 the runners thereon, and has secured the end of said fabric to the moving parts of the machine through which it has to pass for treatment, when said fabric commences to move, it transmits rotary motion to the 25 disks 2, 2^a in the direction indicated by the arrows *c* and *d*, one of said disks being rotated in one direction and the other in the opposite direction. As the disks 2, 2^a are being thus rotated the runners 5, 5^a are also 30 rotated in conjunction therewith, and provided the fabric *b* fails to keep in its proper path (as say by moving toward the right side of the machine) then the weight 8^a on the lever 8 will cause said lever to follow, 35 since it always causes said lever to press upon the edge of the cloth *b*, with the result that as said lever thus moves toward the center of the machine it will cause the shaft 4^a on which the runners 5 are mounted to 40 move in the direction of the arrow *c*; therefore said runners 5 will commence to drag the fabric outwardly in the direction of said arrow *c*, in this manner bringing said fabric to its proper path and simultaneously by 45 said fabric still pressing against the lever 8, the re-adjusting in position of said runners 5 will be effected and will retain the fabric *b* in its normal path.

50 During the time that the fabric is moving through its path toward the right side of the machine the lever 8^a on that side of the machine will be forced outwardly or in the opposite direction to the lever 8 on the left side of the machine as hereinbefore described, with the result that the runners 5^a on said side of the machine will be brought in a direction opposite to that indicated by the arrow *d* and therefore will force back 55 the fabric into its normal position on this side of the machine.

In order that the fabric *b* may be acted upon to the desired extent by the runners 5, 5^a the bearings 4, 4^b upon which said runners 60 65 5, 5^a are mounted may be forced in a down-

ward direction or against the surface of the disks 2, 2^a by an adjusting spring device, or by weighting devices equivalent to same. Said weighting devices 15 (shown in broken lines Fig. 1) I have found as being more efficient when placed upon so as to slide over the upper end of the axial shaft 2^b illustrated by Fig. 1.

The surfaces of the disks 2, 2^a and runners 5, 5^a which have to act upon the surfaces of the fabrics are prepared either by being covered with rubber, leather, felt or the like, or by having serrations or projections, so that they are thereby enabled to exercise greater influence over the fabric which they are conducting to the machine.

Although I have hereinbefore described only one method of arranging the levers 8, 8^a (and the parts used in conjunction with same) which are for contact with the edge of the fabric, and which control the actions of the runners I am aware that many and varied arrangements of these several parts may be made use of without departing from the nature of my invention.

Such being the nature of my said invention, what I claim is:—

1. An improvement in devices for feeding fabrics to stentering machines and the like comprising a freely rotatable disk having its axis approximately at right angles to the plane in which the cloth travels, bearings for said disk, runner bearings mounted to swivel about the axis of rotation of said disk, a shaft mounted in said runner bearings and radially disposed with respect to the axis of the disk, a series of runners rotatably mounted upon said shaft and lever devices for varying the position of said swiveling bearings in accordance with the position of the edge of the cloth.

2. An improvement in devices for guiding or feeding fabrics to stentering machines and the like comprising a freely rotatable disk, bearings for said disk, said bearings being adjustable to retain the axis of the disk in a position approximately at right angles to the plane in which the fabric travels, swiveled bearings, runners mounted in said swivel bearings and mounted to contact with the upper surface of the disk, lever devices for adjusting said swivel bearings, and means contacting with the edge of the fabric for controlling said lever devices.

3. An improvement in devices for guiding or feeding fabrics to stentering machines and the like comprising a freely rotatable disk, bearings for said disk, said bearings being adjustable to retain the axis of the disk in a position approximately at right angles to the plane in which the fabric travels, swiveled bearings, runners mounted in said swivel bearings and mounted to contact with the upper surface of the disk, lever devices for adjusting said swivel bearings,

means contacting with the edge of the fabric for controlling said lever devices, and weighting devices for controlling the pressure of said runners upon the face of the disk.

4. An improvement in devices for guiding or feeding fabrics to stentering machines and the like comprising a freely rotatable disk, bearings for said disk, said bearings being adjustable to retain the axis of the disk in a position approximately at right angles to the plane in which the fabric travels, swiveled bearings, runners mounted in said swiveled bearings and mounted to contact with the upper surface of the disk, lever devices for adjusting said swivel bearings, a lever having means to contact with the edge of the fabric for controlling said lever devices, and an adjustable weighting device for controlling the pressure of the

last mentioned lever against the edge of the fabric.

5. An improvement in devices for guiding or feeding fabrics to stentering machines or the like comprising, a rotatable disk, bearings for said disk arranged to support its axis in a position approximately at right angles to the plane in which the fabric travels, three guiding rollers, two of them in one plane and an intermediate one situated in a higher plane for guiding the fabric passing over the surface of said disk, a counterbalanced bifurcated lever formed for contacting with the edge of the fabric in two positions, one on one side and the other on the other side of the central guiding roller, runners, swivel bearings therefor, and flexible connections from said bifurcated lever to the swivel bearings.

JOHN THORNBER.
